UNITED STATES PATENT OFFICE.

ALEXANDRE M. GREAN, OF NEW YORK, N. Y.

BELTING MATERIAL.

1,183,869.

Patented May 23, 1916.

Application filed July 22, 1915. Serial No. 41,887.

To all whom it may concern:

Be it known that I, ALEXANDRE M. GREAN, a citizen of the United States, residing at New York, in the county of New York and State of New York, have invented new and useful Improvements in Belting Material, of which the following is a specification.

The present invention relates to a length of belting, and the object is to provide an article of manufacture of this character which is flexible and is permanently shaped with a transverse curve throughout its length, said article being of any length desired, so that the same can be sold in a relatively long length, from which portions or sections may be cut as desired for individual use. It may be employed for any suitable purpose, as for instance machine belting, or for surrounding and binding any desired object or article.

In the accompanying drawing, Figure 1 is a view that is diagrammatic in its character, illustrating a form of body blank that may be employed. Fig. 2 illustrates a section of the belting after the same has been given its initial form. Fig. 3 is a detail view of a section of the completed article, and Fig. 4 is a detail perspective view showing a roll of the same.

Similar reference numerals designate corresponding parts in all the figures.

In carrying out the invention, the body blank, which may be of practically any length desired, consists of flexible woven material having longitudinal and transverse threads, as distinguished from diagonally disposed threads. This blank may be of any weight or width, and it is preferably flat. In the probably preferred form, the central portion is substantially inextensible, while the marginal portions are extensible. This may be accomplished by employing in the central portion longitudinal threads 5 of linen, silk, or the like tightly woven, while the marginal longitudinal threads 6 may be cotton, and more loosely woven than the central portion. The transverse threads are shown at 7. This body blank is first saturated with a suitable stiffening material, which is incorporated therein, said stiffening material being glue, starch or the like, and after such incorporation, the said blank is pressed between heated dies that produce therein a transverse curvature, as shown in Fig. 2. This pressing action is continued until the stiffening material sets under the

action of the heat, so that the material assumes a permanently curved shape. In this forming or shaping step, the central portion of the body or blank is contracted, while the marginal portions are extended or stretched.

After the body, which may be designated 8, is thus shaped, an inextensible flexible holding element in the form of a tape 9 is secured longitudinally to the central portion 65 of said body by any suitable means, as for instance, stitches 10, after which the body is again pressed in its transversely curved form between dies under heat. This holding element 9 being substantially inextensible, prevents the longitudinal stretching of the central portion of the belting under longitudinal strain. The result is a smooth, unwrinkled belting having a permanent transverse curve, and is entirely flexible. It may be made in any length desired, dependent upon the length of the original blank, and may be wound into rolls, as shown in Fig. 4, this transverse curvature causing the same to fit snugly and properly about an object having a transversely curved periphery, and also insuring the convolutions against material slipping in the rolls.

From the foregoing, it is thought that the construction, operation and many advantages of the herein described invention will be apparent to those skilled in the art, without further description, and it will be understood that various changes in the size, shape, proportion and minor details of construction may be resorted to without departing from the spirit or sacrificing any of the advantages of the invention.

Having thus fully described my invention, what I claim as new, and desire to secure by Letters Patent, is:—

1. As an article of manufacture, a length of belting comprising a strip of woven flexible material having its longitudinal marginal portions stretched or made longer than the central portions, said woven flexible material being saturated with a stiffening substance and having a permanent transverse curvature.

2. As an article of manufacture, a length of belting of woven flexible material having marginal portions that are woven more loosely than the central portions and having a permanent transverse curvature.

3. As an article of manufacture, a length of belting of woven flexible material having central longitudinal threads that are sub-

stantially inextensible, and marginal threads that are more extensible than the central threads, said belting having a permanent transverse curvature.

5 4. As an article of manufacture, a length of belting of woven material having central longitudinal threads that are substantially inextensible, and marginal threads that are more extensible than said central threads,

10 the marginal portions of said belting being more loosely woven than the central portion, and said belting having a permanent transverse curvature.

5 4. As an article of manufacture, a length
15 of belting formed of flexible woven material having longitudinal and transverse threads, said belting having a stiffening substance incorporated therein and having a permanent transverse curvature throughout its length,
20 and a flexible substantially inextensible

holding element secured longitudinally to the central portion of the belting.

6. As an article of manufacture, a length of belting of woven material having central longitudinal threads that are substantially 25 inextensible, and marginal threads that are more extensible than said central threads, the marginal portions of said belting being more loosely woven than the central portion, and said belting having a permanent transverse curvature, and a flexible substantially inextensible holding element secured longitudinally to the central portion of the body.

In testimony whereof I have hereunto set my hand in presence of two subscribing witnesses.

ALEXANDRE M. GREAN.
